UNITED STATES PATENT OFFICE

2,480,816

EXTINGUISHER FOR ASH TRAYS

John W. Turulis, Gary, Ind.

Application November 9, 1948, Serial No. 59,117

1 Claim. (Cl. 131—256)

This invention relates to an extinguisher for ash trays, and is more particularly concerned with the provision of an extinguisher formed with one or more chambers open at their upper ends to receive and extinguish the lighted ends of cigarettes.

This invention further contemplates the provision of an extinguisher formed with cigarette extinguishing chambers disposed above the base of an ash tray, the outer marginal wall of the chambers being defined by a sleeve which is removable to permit extinguished cigarette butts to fall downwardly by gravity into a bowl or tray portion of the ash tray. In the preferred form of construction, the removable sleeve is formed cylindrical to snugly enclose a reduced upstanding portion provided on a standard projecting upwardly from the base of the ash tray, the upstanding post portion being formed with a plurality of radially disposed ribs for enclosure by the removable sleeve member to define cigarette extinguishing chambers which are open only at their upper ends.

This invention further contemplates the provision of an extinguisher provided with an upstanding post portion formed with one or more grooves, the walls of which extend downwardly and then slope outwardly to terminate adjacent the lower edge of the removable tubular member, whereby the lighted ends of cigarettes are flattened and quickly extinguished when inserted downwardly into a cigarette extinguishing chamber. Upon removal of the sleeve member from the upstanding post portion, any extinguished cigarette butts disposed within said chambers are adapted to fall downwardly and outwardly by gravity from the grooves formed in the upstanding post portion.

As ash trays must be thoroughly cleaned after use to remove cigarette stains and odors, the present invention contemplates the provision of an ash tray having an extinguisher in which the cigarette extinguishing chambers are defined between a removable sleeve and the grooves formed in the upstanding post portion. When the sleeve member is removed from the post portion, it is a relatively simple operation to thoroughly clean the tubular sleeve and the walls of the grooves formed in the upstanding post portion. In the preferred form of construction, the ash tray and the upstanding post portion are formed of glass to facilitate cleaning, while the sleeve member is preferably formed of metal, such as aluminum. By forming the sleeve member of aluminum, or other metal having high conductivity of heat,

the lighted ends of the cigarettes are quickly extinguished after insertion into the cigarette extinguishing chambers by the rapid transfer of heat from a cigarette to the sleeve member.

This invention further contemplates the provision of an extinguisher which is relatively simple and inexpensive in construction, and which insures the user against smoldering cigarettes and resultant fire hazard when lighted cigarette butts are inserted into the cigarette extinguishing chambers.

This invention embodies other novel features, details of construction and arrangement of parts which are hereinafter set forth in the specification and claim and illustrated in the accompanying drawing, wherein:

Fig. 1 is a top plan view illustrating an ash tray embodying features of the present invention.

Fig. 2 is a side elevational view of same.

Fig. 3 is a sectional view taken along the line 3—3 of Fig. 1, illustrating the manner in which the lighted ends of cigarettes are crimped and quickly extinguished when inserted into a cigarette extinguishing chamber.

Fig. 4 is a side elevational view of the upstanding post portion of the extinguisher with the tubular member removed therefrom, to show the manner in which extinguished cigarette butts fall by gravity from the recesses formed in the upstanding post portion downwardly into the tray portion of the ash tray.

Referring now to the drawing for a better understanding of this invention, the device is shown as comprising an ash and cigarette stub receptacle 6 which may be formed of any desired size or shape and of any suitable material, such as glass, metal, plastic or the like. Projecting upwardly from the interior of the receptacle 6 is

provided a standard 7 having a reduced upstanding portion 8 to receive a sleeve 9 which is preferably formed of aluminum or other metal having high heat-conducting properties. A plurality of radially disposed ribs 11 are formed on the reduced upstanding portion 8 to define recesses 12. When the sleeve 9 is mounted in position upon the reduced upstanding portion 8, the walls of each recess 12 and the inner surface of the sleeve 9 define cigarette extinguishing chambers 13 to receive the lighted ends of cigarettes. As illustrated in Figs. 3 and 4, it will be noted that the wall of each recess slopes outwardly at 14 toward the inner face of the sleeve 9.

When the lighted end of a cigarette 16 is inserted downwardly into one of the chambers 13,

the outwardly sloping wall 14 of a recess 12 acts to deflect the lighted end toward and into engagement against the inner surface of the sleeve 9 which then acts to conduct heat from the lighted end of the cigarette to extinguish same. It will also be noted that the lighted end of a cigarette is crimped between the converging surfaces of the wall 14 and sleeve 9 and act to extinguish the lighted end of cigarettes.

An important feature of the present invention resides in the provision of an extinguisher in which the extinguished cigarettes 16 are removed from the cigarette extinguishing chambers 13. This is accomplished by merely raising the sleeve 9 from its position on the reduced upstanding portion 11 to permit the cigarette butts to fall outwardly and downwardly by gravity from their recesses 12 and into any suitable container, such as the cigarette stub receptacle 6. Upon removal of the sleeve 9, it will be noted that all surfaces exposed to contact with cigarettes and ashes may readily be cleaned to remove stains or cigarette odors.

While the invention has been shown and described as embodying a reduced upstanding portion formed with radially disposed ribs enclosed by a cylindrical sleeve, it is contemplated that the sleeve 9 may be square, rectangular, or other shape in cross-section to define cigarette extinguishing chambers on an upstanding post formed with trough-shaped recesses. While it is contemplated that this invention may be embodied in various forms, it is desirable that the cigarette receiving chambers 13 should be formed to snugly receive the lighted ends of cigarettes in order to exclude air. An abutment shoulder 17 is provided at the inner end of the reduced portion 8 for line contacting engagement with the sleeve.

While this invention has been shown in but one form, it is obvious to those skilled in the art that it is not so limited but is susceptible of various changes and modifications without departing from the spirit and scope of the claimed invention.

I claim as my invention:

In an article of the character described, a standard formed with a reduced upstanding portion, a sleeve removably positioned on said reduced upstanding portion, said reduced portion being formed with a groove to define with said sleeve a cigarette extinguishing chamber to snugly receive the lighted end of a cigarette, the wall of said groove being inclined outwardly toward and terminating at the inner face of said sleeve to flatten the lighted end of a cigarette inserted into said chamber to extinguish the cigarette and to cause the cigarette to fall from said groove by gravity upon removal of said sleeve from said reduced portion.

JOHN W. TURULIS.
